UNITED STATES PATENT OFFICE.

FRANK E. HERDMAN, OF WINNETKA, ILLINOIS.

BRAKE MECHANISM FOR ELECTRIC ELEVATORS.

SPECIFICATION forming part of Letters Patent No. 568,569, dated September 29, 1896.

Application filed October 5, 1895. Serial No. 564,734. (No model.)

To all whom it may concern:

Be it known that I, FRANK E. HERDMAN, a citizen of the United States, residing at Winnetka, county of Cook, and State of Illinois, have invented a new and useful Improvement 5 in Brake Mechanism for Electric Elevators, of which the following is a full, clear, and exact description, reference being had to the accompanying drawings, which form a part of this 10 specification.

This invention is especially adapted for use with electric motors used to operate elevating apparatus.

The purpose or object of this invention is 15 to provide brake-operating mechanism so that the brake shall not be removed until sufficient power is on the machine to enable it to move the load in the direction required, or at least to prevent the load overcoming 20 the motor and slipping back.

I will first describe my invention as illustrated in the drawings, and then particularly point out the invention in the claims.

In the drawings, Figure 1 is an end view. 25 Fig. 2 is an electrical diagram. Fig. 3 is a vertical section through the switch-box.

E is an electric motor; e, its shaft. On this shaft is the brake-wheel S, having the brake-band Q and brake-lever Q'. This 30 brake-lever Q' is pivotally attached to the core Q⁷ of the solenoid-magnet Q⁶. This solenoid-magnet is in shunt with the main circuit of the source of current supply to the motor, and the current to said magnet is controlled by the motor-switch, which in turn 35 is controlled by the operating-shaft P'. To particularize more fully as to the circuit connections in relation to this magnet Q⁶, X is the snap-switch, composed of the brushes a 40 a' a² a³, the brushes a² and a³ being insulated from each other by insulation a¹⁰¹ and the brushes a and a' being in electrical connection with each other by conductive portion a¹⁰² of hub of switch, but the two pairs of 45 brushes being insulated from each other by the insulation a¹⁰⁰.

Dependent upon which direction the snap-switch is turned the brush a makes contact with contacts a⁴ or a¹¹, brush a' with contacts a⁵ or a¹⁰, brush a² with contacts a⁶ or a⁹, and brush a³ with contacts a⁷ or a⁸, the con-

tacts a⁵ and a⁹ being connected with each other, and so are contacts a⁶ and a¹⁰ and contacts a and a⁸ and a⁴ and a¹¹. The conductive portion a¹⁰² is in electrical connection 55 with one pole of current supply.

The contacts a⁴ and a¹¹ are in electrical connection with the solenoid X'. The solenoid X' is also in direct electrical connection with the wire leading from the other pole of 60 current supply. The contacts a⁴ and a¹¹, by means of a wire, are in direct electrical connection with the solenoid Q⁶. The return-wire from the solenoid Q⁶ passes to and is connected with the contacts a⁸ and a⁷. A 65 wire runs from the brush a³ to the field resistance a¹⁴, from thence through the resistance-arm a¹² to the other source of current supply, (the field connections not being shown in this drawing.) From the contact a⁵ a wire 70 runs to the armature. From the armature a wire leads to contact a⁶. From brush a² a wire leads to the armature-resistance plate a¹⁰⁴.

When the switch is thrown either to the right or to the left, the brushes make contact 75 with one or the other of said contacts. The only difference in the series of contacts which the brushes make contact with is causing the current to pass in opposite direction to the armature. Supposing the connection to be 80 made with the upper set of contacts in the drawing—to wit, a⁴, a⁵, a⁶, and a⁷—the current, as far as the armature is concerned, passes from the brush a' to the contact a⁵, from the contact a⁵ to the armature of the 85 motor, from the armature of the motor back to contact a⁶, from thence to the brush a², from the brush a² to the armature-resistance plate a¹⁰⁴, thence from the resistance-arm a¹² to the other pole of current supply. At the 90 same time the solenoid X' is energized, and, being connected to the resistance-arm a¹², operates it to move it to cut out resistances in the armature-circuit. At the same time the solenoid Q⁶ is energized by means of the 95 brush a making contact with the contact a⁴, and the return current from the solenoid passes to the contact a⁷, from thence to brush a⁵, and from thence to the field-resistance plate a¹⁴, and from thence from the resistance-arm a¹² back to the other pole of the source of 100 current supply.

trical connections from the source of current supply to said electric device, switch mechanism controlled by the motor-controlling mechanism whereby the electric device is 5 energized, when current is admitted to the motor, the core of said electric device being weighted.

In testimony of which invention I have hereunto set my hand.

FRANK E. HERDMAN.
